UNITED STATES PATENT OFFICE

JOHN B. COOLIDGE, OF BOSTON, MASSACHUSETTS.

IMPROVEMENT IN GAS-BURNERS.

Specification forming part of Letters Patent No. **58,606**, dated October 9, 1866.

To all whom it may concern:

Be it known that I, JOHN B. COOLIDGE, of Boston, in the county of Suffolk and State of Massachusetts, have invented an Improved Gas-Burner, of which the following is a full clear, and exact description, reference being had to the accompanying drawings, making part of this specification, in which—

Figure 1 is a perspective view of my improved gas-burner. Fig. 2 is a central vertical section through the same. Fig. 3 is a view of the tip detached.

My invention consists in a gas burner the orifice at the tip of which may be contracted or expanded as required, thus particularly adapting it for use in connection with machines for making gas from naphtha or other light hydrocarbons, where it is desirable to increase the size of the orifice of the burner when a poor quality of gas is being used.

To enable others skilled in the art to understand and use my invention, I will proceed to describe the manner in which I have carried it out.

In the said drawings, A is the burner, the portion *a* of which is made slightly tapering, and over this portion is fitted an exterior tube, *b*, which surrounds the tip *c*. This tip is made tapering, and is split, so that it will spring apart, as seen in Fig. 3. The upper portion of the tip *c* is enlarged, and the lower end is provided with a screw-thread, which fits into a corresponding screw-thread on the inside of the burner A, a pin, *d*, passing through the exterior tube, *b*, and the slit in the tip *c*, so that the tube and tip will turn together, while the tip is permitted to move vertically within the tube *b*, and thus as the tube *b* is turned in one direction the tip is raised, projecting its upper end farther out from the top of the tube *b* and allowing it to spring apart, and thus increase the size of the orifice 4 as required, while on turning the tube *b* in the opposite direction the tip is withdrawn, exposing less of the orifice above the top of the tube *b*, and at the

same time causing the inclined sides 5 to press against the inside of the tube *b* and force the two portions of the tip together, so as to diminish the size of the orifice. The spring of the split portion of the tip *c*, while it causes the inclined sides 5 to press against the inside of the tube *b* and prevent the leakage of gas at this point, also tends to draw the tapering portion *a* of the burner into the corresponding portion of the exterior tube, *b*, and thus make a gas-tight joint between the two. The size of the flame may thus be regulated with a great degree of nicety without varying the pressure of the gas on the burner, which cannot be attained by the use of the ordinary stop-cock, thus particularly adapting this burner for use in connection with machines for making gas from naphtha and other light hydrocarbons, where the quality of the gas frequently varies, a rich quality of gas requiring a burner with a smaller orifice, while when the gas becomes mixed with too large a proportion of air a burner with a larger orifice is required. I do not, however, limit myself to its use in connection with these machines, but intend to apply it wherever it may be found desirable; neither do I confine myself to the exact construction here shown, as it is evident that it may be varied without departing from the spirit of my invention. For instance, the tip may be secured permanently to the burner, and the exterior or confining tube, *b*, be moved up and down by hand; or the exterior tube, *b*, may be attached permanently to the end of the gas-pipe and have a screw-thread cut in its interior, into which the split tip may be screwed.

What I claim as my invention, and desire to secure by Letters Patent, is—

The split tip *c*, in combination with the exterior tube, *b*, operating substantially as described.

J. B. COOLIDGE.
